UNITED STATES PATENT OFFICE.

WILLIAM OTTO ARZINGER, OF NASHVILLE, TENNESSEE.

SAND-SEPARATOR.

1,333,197.

Specification of Letters Patent.

Patented Mar. 9, 1920.

Application filed November 1, 1917. Serial No. 199,712.

To all whom it may concern:

Be it known that I, WILLIAM O. ARZINGER, a citizen of the United States, and a resident of Nashville, in the county of Davidson and 5 State of Tennessee, have invented a new and useful Improvement in Sand-Separators, of which the following is a specification.

My invention relates to improvements in devices for separating materials, more particularly for separating sand or grit from graphite in the process of refining the latter, and it consists in the combinations, constructions and arrangements herein described and claimed.

15 An object of my invention is to provide a simple device by means of which the graphite may be separated from the sand continuously, that is to say, without necessitating the stopping of the apparatus to 20 take away portions of the separated graphite.

A further object of my invention is to provide a separator which is of simple construction, has few parts, is not easily liable 25 to get out of order, and which may be readily assembled.

Other objects and advantages will appear in the following specification, and the novel features of the invention will be particularly 30 pointed out in the appended claim.

My invention is illustrated in the accompanying drawings forming part of this application, in which:

Figure 1 is a central section through the 35 device.

Fig. 2 is a plan view.

Fig. 3 is a section on the line 3—3 of Fig. 1, and

Fig. 4 is a section on the line 4—4 of 40 Fig. 1.

In carrying out my invention I provide a casing 1, this casing being preferably of a cylindrical shape and having a bottom 2 which is provided with a central flanged 45 opening 3.

Extending upwardly through this opening 3 is a pipe 4. The upper end of the casing has a conical shape as shown at 5, and terminates in a central flanged opening 6.

A pipe 7 extends downwardly through the opening 6. This pipe is provided with a series of perforations 8 but is closed at its bottom with a conical member 9. At the 55 end of the pipe 7 is a deflector or baffle 10. This baffle is of conical shape and is pro-

vided with a sleeve 11 which is threaded to engage the threaded end of the pipe 7. The openings 3 and 6 are also threaded so as to hold their respective pipes 4 and 7, securely. 60

It will be noted that the pipe 4 passes through the bottom 8 and extends partly into the interior of the casing 1. A door 12 is disposed at the bottom of the casing on one side thereof.

From the foregoing description of the various parts of the device the operation thereof may be readily understood. The mixed sand and graphite is forced through the pipe 4 by any suitable means. In a co-

pending application I have set forth the means by which this is done, this means being a fan or blower. The graphite and sand passes up through the pipe 4, being projected against the baffle or deflector 10. The

70 sand having a slightly greater specific gravity than the graphite, tends to bound backwardly toward the bottom of the cylinder or casing; the elasticity of the sand being greater also, tends to cause this action. 75

The graphite being of a flaky nature, is caught by the air current and passes around the edge of the deflector or baffle 10 and then is drawn through the perforations 8, into the pipe 7 and then out through the

80 pipe 7. I find that the perforated pipe 7 aids in separating a considerable quantity of the sand from the graphite which has been carried around the edge of the deflector by the air currents. Apparently, the graph- 90

ite being in the form of flakes is more easily carried along by the currents, or turned from its path into the path of the currents. These openings 8, as it will be seen, are not so close as to form a grating, but are prefer- 95

ably arranged in rows, leaving a considerable space between the rows so that the air currents actually change their courses in order to pass through these perforations.

The sand which falls downwardly collects 100 below the end of the pipe 4 on the bottom of the casing 1, and may be removed from time to time by opening the door 12.

The device works continuously, and may be easily taken apart for inspection or re- 105 pair, although the few parts and the relative simplicity of the device obviates the necessity of much attention on the part of the user of the device.

I claim:

110 A sand separator comprising a cylindrical casing; an inlet pipe, for conveying air,

flake graphite, and sand, extending into the bottom of the casing, the end of the inlet pipe being above the bottom; said casing having a conical top provided with an opening; a discharge pipe extending through said opening in the top of the casing; said discharge pipe having a portion extending downwardly into the casing, said downwardly extending portion having perforations in its sides, for the passage of air and graphite; the bottom end of the pipe being closed with a hollow conical member; and

also provided with a hollow conical member against which said particles may impinge having a sleeve arranged to receive the end 15 of said exit pipe; said second named hollow conical member having a conical surface concentric with the closure to the exit pipe, whereby a continuous conical hollow baffle is formed at the end of the exit pipe to deflect 20 the impinging sand particles; and said hollow baffle being spaced from the end of the inlet pipe, substantially as described.

WILLIAM OTTO ARZINGER.
